(57) **CLAIM**

The ornamental design for a charging station for electric vehicles as shown and described.

DESCRIPTION

FIG. 1 is a front, right and top perspective view of a charging station for electric vehicles showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of encircled portion 9 of FIG. 1; and,
FIG. 10 is an enlarged view of encircled portion 10 of FIG. 1.
The broken lines depict portions of the charging station for electric vehicles that form no part of the claimed design.

1 Claim, 10 Drawing Sheets
